UNITED STATES PATENT OFFICE.

AUGUST E. ROEVER, OF BUFFALO, NEW YORK.

FASTENER FOR ROOFING.

No. 876,843.

Specification of Letters Patent.

Patented Jan. 14, 1908.

Application filed November 19, 1906. Serial No. 343,994.

To all whom it may concern:

Be it known that I, AUGUST E. ROEVER, a citizen of the United States, resident of Buffalo, county of Erie, and State of New York, have invented a new and useful Improvement in Fasteners for Roofing, of which the following is a specification, the principle of the invention being herein explained, and the best mode in which I have contemplated applying that principle, so as to distinguish it from other inventions.

My invention relates to improved means for securing roofing, to the roof-boards, particularly prepared roofing, such as tarred felt, granite roofing, and the like, which usually comes in long strips made up in the form of rolls. While thus primarily designed for use with roofing of this character, it will be obvious that the device in hand is capable of quite general application, wherever the several advantageous features presented by such fastener are appreciated.

Said invention, then, consists of means hereinafter fully described and particularly set forth in the claims.

The annexed drawing and the following description set forth in detail certain means embodying the invention, such disclosed means constituting but one of various forms in which the principle of the invention may be used.

In said annexed drawing: Figure 1 represents in perspective a broken section of roofing, in connection with which my improved fastener has been utilized for securing the same to the roof paper; Fig. 2 is a transverse cross section through a section of such roofing, showing in side elevation one of my fasteners *in situ*; Fig. 3 is a perspective view of one form of my fastener as it appears previous to its application to the roofing; and Fig. 4 represents, likewise in perspective, a slightly modified form of such fastener.

The method practically universally employed for securing prepared roofing material to the roof, as is well known, consists simply in tacking down the overlapping edges of such roofing. Washers are usually employed in connection with the nails, or else nails with broad heads, in order to secure a broad bearing surface and to prevent the heads of the nails from breaking through the roofing material. The only precaution taken to prevent leakage at the several points of attachment, the roofing material being obviously punctured, has been to

spread over the same a coating of tar or waterproofing material.

The above method of attaching roofing has long been considered objectionable, but its use has continued for want of a suitable substitute for the nails. Among other objections there may be enumerated the fact that the boards of the roof usually shrink more or less after the construction of a building, and such shrinkage causes the relative movement of the nails thereby tearing the material and leaving a space around the nail through which water may enter. This defect is accentuated by the expansion and contraction to which changes of temperature subject the roofing material itself, the general result being that, in the course of a relatively short time, the roofing has worked loose about the nails sufficiently to allow the entrance of moisture, with the consequent very rapid deterioration both of the adjacent material and of the roof proper underneath.

It should be added to the above that another similar source of much annoyance in the use of nails for holding down the roofing arises from the fact that where a nail happens to be driven into a crack, as between adjacent roof boards, in addition to the roofing material being torn as already noted, there is a pronounced tendency for the nail to actually work entirely loose and drop out of the roofing. Obviously the hole thus left in such roofing is a fruitful cause of trouble, as any person of experience with roofs of this kind can witness.

The device which I propose to utilize in place of nails for securing the roofing material to the roof comprises in its simplest form, Fig. 3, merely a narrow metallic strip A formed with an aperture a near one end, adapted to allow the passage therethrough of a nail for the purpose of attaching the strip to the roof boards. The other end of the strip is doubled over upon itself, the doubled-over portion a' terminating short of the nail-receiving aperture a and being provided with a transversely-disposed prong a². As shown, this prong is of substantially triangular form, and is slightly recurved, that is, its point is inclined towards the doubled-over end of the fastener. In the modified form of fastener shown in Fig. 4, no change is made from the construction just described except that, in place of being formed with an opening for the reception of a nail, by means of which the

fastener is designed to be tacked fast, such under portion of the fastener is formed with an integral downwardly-turned point a^3 . This point is designed to be utilized in tacking the fastener down, thus much simplifying the operation and rendering unnecessary the use of any nails whatever.

In applying the fastener as will be evident from an inspection of Figs. 1 and 2, the main portion, referred to as the under portion in the above description, is nailed down either by means of a nail through opening a or by means of the integral point a^3 , where the latter form is used, along the upper edge of the 10 undermost of the overlapping sheets of roofing material. The upper sheet is then moved into place so as to have its lower edge clasped between such under portion and the doubled-over portion a' of the fastener. The 15 doubled-over portion a' is thereupon hammered down, the transversely-disposed prong a^2 piercing such upper layer of roofing and being clenched upon the under portion, as clearly shown in Fig. 2. The point where 20 such piercing of the upper layer takes place, it is obvious from the relative lengths of the two portions of the fastener as above delineated, will be some distance below the point of attachment of the fastener, or, in other 25 words, the point where the lower sheet of roofing is pierced. Any moisture, hence, that will percolate through the puncture in the upper sheet, it is obvious, will escape between the sheets downwardly without running 30 across or in proximity to the opening in the lower sheet. The roof boards underneath are hence kept absolutely dry. At the same time, both sheets are very securely held in place, for the upper edge of the under 35 sheet is nailed down in much the same fashion as in the old method, while the lower edge of the upper sheet is equally securely held down by the fastener which clasps it and, by being clenched in the manner described, makes release 40 of the sheet impossible. Where it becomes necessary to have two sheets overlap laterally, as only infrequently happens where the roofing is horizontally disposed in order to piece out a short sheet of the material, or 45 as will be almost entirely the case in the use of vertically disposed roofing, my improved fastener can still be used with equally efficacious results in securely clenching such roofing in place while preventing the passage of 50 water therethrough. It only becomes necessary in this use of the fastener to dispose the same at a slight downward inclination to the vertical line of the lap, in order that the water may not follow the under portion of the fastener to the point where the under layer of 55 roofing is pierced, as it might do if the clip were horizontally disposed. To insure the proper disposition, therefore, of the fastener when utilized in this latter connection, I preferably form the same not out of a straight 60

metal strip, as in the case of the standard form of fastener as above, but out of one of V form, whereby, upon being doubled over, the form A' , shown in Fig. 1, results, differing only from the standard form in that the doubled-over edge of the fastener is at an angle with its lateral edges instead of being at right angles thereto, as in the standard form. The method of attachment and the clenching of the upper doubled-over portion is exactly 75 the same in this case as the form first described.

It will be seen, from the foregoing description, that by the employment of this type of fastener in place of nails or the like, 80 a perfect joint is secured, without sacrificing in the least the permanence with which the roofing is held down. It is immaterial whether the timbers of the roof shrink or not, or whether, because of shifting of the roofing sheets with the alternation of summer heat and winter cold, such sheets be drawn more or less from about the nail-heads, for these are at all times securely covered over with the upper sheet. At the same time, such 85 upper sheet is just as firmly bound to the lower as though the nail in question actually pierced it also. Such fastener has the further advantage of being quite inexpensive. In 90 fact, in material it does not represent a much greater outlay than the old-fashioned washer heretofore used in connection with the nails. Its attachment, furthermore, involves the use of no new tools nor the expenditure of much additional labor, while the results 95 above noted as being obtained by its use clearly commend its general employment for the purpose stated.

Having thus described my invention in detail, that which I particularly point out and distinctly claim, is:—

1. A fastener for roofing comprising a metallic strip doubled over upon itself, the doubled-over portion being provided with a prong adapted to be driven through the roofing material to contact with the lower portion of said metallic strip.

2. A fastener for roofing comprising a metallic strip doubled over upon itself, the doubled-over portion being provided with a transversely disposed prong adapted to be driven through the roofing material to contact with the lower portion of said metallic strip.

3. A fastener for roofing comprising a metallic strip formed at one end with a point adapted to be driven into the roof boards, such strip being doubled over upon itself, the doubled-over portion being shorter than the other portion and terminating in a prong adapted to be driven through the roofing material to contact with the lower portion of said metallic strip.

4. The combination with overlapping sheets of roofing; of a fastener therefor com-

- prising a metallic strip secured to the under sheet and doubled over upon itself so as to clasp the edge of the upper sheet, such doubled-over portion of the strip being provided with a triangular prong disposed interiorly of its lateral edges and adapted to be driven through such upper sheet and to contact with the lower portion of said metallic strip.
5. The combination with overlapping sheets of roofing; of a fastener therefor comprising a metallic strip secured to the under sheet and doubled over upon itself so as to clasp the edge of the upper sheet, such doubled-over portion of the strip being provided with a transversely disposed, slightly recurved prong adapted to be driven through such upper sheet to contact with and be clenched upon the lower portion of such strip.
10. 5. The combination with overlapping sheets of roofing; of a fastener therefor comprising a metallic strip secured to the under sheet and doubled over upon itself so as to clasp the edge of the upper sheet, such doubled-over portion being provided with a transversely disposed, slightly recurved prong adapted to be driven through such upper sheet to contact with and be clenched upon the lower portion of such strip.
15. 6. The combination with overlapping sheets of roofing; of a fastener therefor comprising a metallic strip formed at one end with a point adapted to be driven through
- the under sheet and doubled over upon itself 25 so as to clasp the edge of the upper sheet, such doubled-over portion of the strip being provided, short of the point of attachment of the under portion of such strip, with a prong disposed interiorly of the lateral edges of 30 such doubled-over portion and adapted to be driven through such upper sheet and contact with such lower portion of the metallic strip.
7. The combination with overlapping sheets of roofing; of a fastener therefor comprising a metallic strip secured to the under sheet and doubled over upon itself so as to clasp the edge of the upper sheet, such doubled-over portion being provided with a transversely disposed prong adapted to be 40 driven through such upper sheet to contact with and be clenched upon such lower portion.

Signed by me, this 10th day of November, 1906.

AUGUST E. ROEVER.
